Primary Examiner — Brian N. Vinson(74) Attorney, Agent, or Firm — Heslin Rothenberg Farley and Mesiti PC(57) CLAIM

The ornamental design for a lighting fixture, as shown and described.

DESCRIPTION

FIG. 1 is a left perspective view of a lighting fixture according to the new design;

FIG. 2 is a right perspective view thereof;

FIG. 3 is a top view thereof;

FIG. 4 is a front elevational view thereof;

FIG. 5 is a left side elevational view thereof;

FIG. 6 is a right side elevational view thereof;

FIG. 7 is a bottom view thereof;

FIG. 8 is another front elevational view thereof; and,

FIG. 9 is another left perspective view thereof.

The broken lines in the drawing illustrate portions of the lighting fixture which form no part of the claimed design.

1 Claim, 5 Drawing Sheets(56)
